CUTTER DISENGAGING DEVICE

Russell E. Benner, New York, N. Y., assignor, by
mesne assignments, to Remington Rand Inc.,
Buffalo, N. Y., a corporation of Delaware

Application November 27, 1937, Serial No. 176,791

10 Claims. (Cl. 30—43)

This invention relates to improvements on electric dry shavers of a well known type and particularly to means for disengaging the inner cutter.

5 Electric dry shavers now in wide use include a motor housing to which is secured a fixed shearing head having a reciprocating inner cutter mounted therein. According to prevailing practice, the shearing head is so secured to the motor casing that the inner cutter is thereby held in locked engagement with the motor operative parts and remains so locked until the entire shearing head is disengaged from the motor casing. This arrangement, therefore, does not permit the inner cutter to be removed without first disengaging the entire shearing head.

The purpose of this invention is to provide an improvement that facilitates the removal of the inner cutter without having first to disengage the fixed outer shearing head from the motor casing. The improvement lies in the provision of a trigger which extends out of one side of the motor casing, the depression of which releases the inner cutter to permit easy removal thereof.

25 Another object of this invention is to provide a simple and time-saving means for disengaging the cutters for cleaning purposes.

Other and further objects of this invention will appear more fully from a detailed description of 30 the device as hereinafter disclosed.

This invention resides substantially in the combination, construction, arrangement, and the relative location of the parts, all as will be shown in greater detail in the following specification in 35 connection with the illustrations and drawing therein, in which:

Fig. 1 is a side elevational view of a fragmentary portion of a shaver showing part of the device covered by this invention;

40 Fig. 2 is a cross sectional view of the same device taken substantially along line 2—2 of Fig. 1;

Fig. 3 is a view of the same device taken substantially along line 3—3 of Fig. 2;

Fig. 4 is an end view of the same device shown 45 in cross section with the trigger depressed and with the parts disengaged for removal of the inner cutter;

Fig. 5 is a side elevational view similar to that in Fig. 1, but with the side casing removed, parts 50 broken away, and the inner cutter partly removed; and

Fig. 6 is a view taken substantially along line 55 6—6 of Fig. 5 with parts broken away.

Like characters of reference refer to like parts 60 in all views.

Referring to the drawing, a fragmentary portion of a casing 20 of any well known electric dry shaver is shown. Said casing 20 encloses a motor also well known and not described save for a few essential parts. Near the top of casing 20, on the front face thereof, is a rectangular slot 21 within a depression 22. Projecting out of said rectangular slot 21 is the end of a trigger 23. Secured to casing 20 is a fixed outer cutter 24, within which is reciprocally mounted an inner cutter 25. The fixed outer cutter 24 is secured to casing 20 by a screw 26.

As hereinbefore indicated, within casing 20 is a well known motor and its mechanism, of which 15 27 represents a motor driven rotatable shaft in two distinct parts. The lower part 28 of said shaft 27 has a pair of lugs 29 oppositely positioned near the upper end thereof. The upper part 30 of shaft 27 has at its extreme end an eccentric cam 31 and at its lower end a sleeve 32 having a shoulder 33. Within said sleeve 32 is a pair of 20 grooves 34 serving as guideways for lugs 29 on the lower part 28 of shaft 27. Sleeve 32 slidably engages the upper portion of the lower part 28 of shaft 27. A spring member 35 is loosely seated on top of lower part 28 of shaft 27 and is positioned wholly within sleeve 32.

On each side of shaft 27 is a pair of spring-pressed plungers 36, each having a shoulder 38. Said spring-pressed plungers 36 are supported 30 at their lower ends by a supporting plate 37 through which shaft 27 extends.

Pressure plate 39 is movably seated on shoulders 33 and 38 of sleeve 32 and plungers 36 respectively. Through the center of pressure plate 39 is an aperture 40. While aperture 40 has enough clearance for cam 31 and upper part 30 of shaft 27 to pass through, shoulder 33 of sleeve 32 acts as a stop therefor. On each side of aperture 40 are substantially similar apertures 41, 40 through which the upper parts of plungers 36 extend. Shoulders 38 of plungers 36 act as stops for apertures 41.

Secured to the inner rear wall of casing 20 by screws 42 is a bracket 43 having a head piece 44 which is rolled into a cylindrical shape forming a bore through which a pivot pin 45 extends.

Trigger 23 is pivotally secured to head piece 44 of plate 43 by pivot pin 45, and has substantially the shape of a fork, formed by arms 46 and 47 thereof. Arm 46 is the shorter of the said arms and is joined to arm 47 by a pair of small rivets 48. Arms 46 and 47 extend transversely on each side of shaft 27 and have arcuate pro-

2
jections 49 protruding from their respective lower sides.

Inner cutter 25 is provided with a groove 50 which engages cam 31 on the top of the motor 5 driven and rotatable shaft 27. Cutouts 51 engage the tip ends of spring-pressed plungers 36.

Figs. 1, 2, and 3 show the inner cutter 25 in locked engagement with cam 31 of shaft 27 and spring-pressed plungers 36. The commercially 10 known means to remove inner cutter 25 is by loosening screw 26, removing the fixed outer cutter 24 and then sliding out the inner cutter 25.

In the operation of the device covered by this invention, to remove inner cutter 25, the trigger 15 23 is depressed, moving it from the position shown in Fig. 2 to that shown in Fig. 4. By so doing, the arcuate projections 49 act upon the plate 39 to depress the upper portion 30 of the shaft 27 against the tension of spring 35. Likewise plate 39 bears down on shoulders 38 of 20 spring-pressed plungers 36. By this means cam 31 and spring-pressed plungers 36 are respectively disengaged from groove 50 and cut-outs 51 of inner cutter 25, thereby permitting the easy 25 removal of the inner cutter, as partly shown in Fig. 5.

While I have described what I consider to be a highly desirable embodiment of my invention, it is obvious that many changes in form could be 30 made without departing from the spirit of my invention, and I, therefore, do not limit myself to the exact form herein shown and described, nor to anything less than the whole of my invention as hereinbefore set forth, and as hereinafter 35 claimed.

What I claim as new, and desire to secure by Letters Patent, is:

1. The combination in a dry shaver of a motor casing, a rotatable shaft having an upper and lower section, the upper section being slidably mounted upon the lower section, longitudinal lugs near the top of said lower section, a sleeve at the base of said upper section having longitudinal grooves therein as guideways for 40 said lugs, a spring member positioned between the lower and upper sections of said shaft within said sleeve, spring-pressed pins, shoulders on said sleeve and pins supporting a pressure plate, a fork-shaped trigger pivotally secured to said casing and bearing down on said pressure plate, an eccentric cam on said upper section, a fixed outer cutter, an inner cutter reciprocally mounted 45 therein having engagement with said cam and pins, and means on said trigger to release the inner cutter from said cam and pins.

2. The combination in a dry shaver of a motor casing, a rotatable shaft having an upper and lower section, the upper section being slidably mounted upon the lower section, longitudinal 50 lugs near the top of said lower section, a sleeve at the base of said upper section having longitudinal grooves therein as guideways for said lugs, a spring member positioned between the lower and upper sections of said shaft within said sleeve, spring-pressed pins, shoulders on said sleeve and pins supporting a pressure plate, a fork-shaped trigger bearing down on said pressure plate, an eccentric cam on said upper section, a fixed outer cutter, and an inner cutter reciprocally 55 mounted therein having engagement with said cam and pins.

3. The combination in a dry shaver of a motor casing, a rotatable shaft having an upper and lower section, the upper section being slidably 60 mounted upon the lower section, longitudinal 70

lugs near the top of said lower section, a sleeve at the base of said upper section having longitudinal grooves therein as guideways for said lugs, a spring member positioned between the lower and upper sections of said shaft within said 5 sleeve, spring-pressed pins, shoulders on said sleeve and pins supporting a pressure plate, an eccentric cam on said upper section, a fixed outer cutter, an inner cutter reciprocally mounted therein having engagement with said cam and pins, and means for depressing said pressure plate to disengage said cam and pins, thereby permitting removal of said inner cutter.

4. The combination in a dry shaver of a motor casing, a rotatable shaft having an upper and lower section, the upper section being slidably mounted upon the lower section and having a cam thereon adapted to engage and drive a cutter member, longitudinal lugs near the top of said lower section, a sleeve at the base of said upper section having longitudinal grooves therein as guideways for said lugs, a spring member positioned between the lower and upper sections of said shaft within said sleeve, spring-pressed pins cooperating with said cutter, shoulders on 20 said sleeve and pins, a trigger pivotally secured to the casing, and means actuated by said trigger for slidably forcing the upper section down upon the lower section of the shaft to disengage said cutter from said cam and pins. 30

5. The combination in a dry shaver of a motor casing, a rotatable shaft having an upper and lower section, the upper section being slidably mounted upon the lower section, longitudinal lugs near the top of said lower section, a sleeve at the base of said upper section having longitudinal grooves therein as guideways for said lugs, spring-pressed pins, shoulders on said sleeve and pins, an eccentric cam on said upper section, a fixed outer cutter, an inner cutter reciprocally 40 mounted therein having engagement with said cam and pins, and resilient means for disengaging said inner cutter.

6. The combination in a dry shaver of a motor casing, a rotatable shaft having an upper and lower section, the upper section being slidably mounted upon the lower section, longitudinal lugs near the top of said lower section, a sleeve at the base of said upper section having longitudinal 50 grooves therein as guideways for said lugs, shoulders on said sleeve, a fixed outer cutter, an inner cutter reciprocally mounted therein, and resilient means for readily removing the inner cutter.

7. The combination in a dry shaver of a motor casing, a rotatable shaft having an upper and lower section, the upper section being slidably mounted upon the lower section, longitudinal lugs near the top of said lower section; a sleeve at the base of said upper section having longitudinal 60 grooves therein, a fixed outer cutter, an inner cutter reciprocally mounted therein, and resilient means for removing the inner cutter.

8. A dry shaver of the type described including a motor casing, a member slidably mounted upon a rotatable shaft, a spring loosely held between said arm and rotatable shaft, spring-pressed plungers, an outer cutter, an inner cutter reciprocally mounted therein engaging said arm and spring-pressed plungers, and means operable on the said arm and spring-pressed plungers to disengage them from the inner cutter. 65

9. A dry shaver of the type described including a motor casing, a member slidably mounted upon a rotatable shaft, a spring between said arm and 70

5 rotatable shaft, spring-pressed plungers, an outer cutter, an inner cutter reciprocally mounted therein and engaging said arm and spring-pressed plungers, and a pivotal lever operable on said arm and spring-pressed plungers to release them from engagement with said inner cutter while the outer cutter remains secured to the motor casing.

10 In a device of the type described, a motor 10 casing, a rotatable shaft having an upper and lower section, the upper section being slidably mounted upon the lower section, longitudinal lugs near the top of said lower section, a sleeve at the base of said upper section having longi-

tudinal grooves therein as guideways for said lugs, a fixed outer cutter, an inner cutter reciprocally mounted therein, spring-pressed pins adapted to maintain said inner cutter in engagement with said outer cutter, an eccentric cam on said upper shaft section adapted to engage and drive said inner cutter, shoulders on said sleeve and pins, a pressure plate carried on said shoulders, and a fork-shaped trigger adapted to depress said plate thereby permitting the removal of said inner cutter without detaching said outer cutter.
